MECHANISM FOR INTERMITTENT MOVEMENT

William Ganz, Teaneck, N. J., assignor to Ganz Brothers, Bergenfield, N. J., a firm

Application May 13, 1946, Serial No. 669,287

18 Claims. (Cl. 74—116)

1

This invention relates to mechanism for providing certain types of mechanical movements. More particularly, this invention relates to novel mechanism for converting continuous mechanical movement to intermittent movement.

Prior to this invention, a number of different types of mechanism have been suggested for converting continuous movement to intermittent movement. While some of them have been employed in the machinery field, all of them have for one reason or another failed to be completely satisfactory especially where high speed is a requisite. Consequently, this invention has been made to provide various mechanisms which because of the type and relationship of parts are rugged and easily assembled and will operate at high speeds over a considerable period of time without necessity of repair or replacement. The foregoing as well as other advantages of this invention will be readily apparent from the following description and accompanying drawings, wherein:

Fig. 1 is a perspective view of a drive mechanism enclosed in an oil filled housing embodying my invention.

Fig. 2 is a fragmentary top plan view of one embodiment of the invention and is taken on line II—II of Fig. 3 in the direction of the arrows.

Figs. 3, 4 and 5 are side views of the mechanism shown in Fig. 2 and show the various relationships of parts at different stages of operation.

Fig. 6 is a fragmentary side view of another embodiment of the invention.

Fig. 7 is a fragmentary top plan view of the mechanism shown in Fig. 6.

Fig. 8 is a side view of another embodiment of the invention.

Fig. 9 is a top plan view of the mechanism shown in Fig. 8.

Fig. 10 is a side view of another embodiment of the invention.

Fig. 11 is a top plan view of the mechanism shown in Fig. 10.

Fig. 12 is a side view of still another embodiment of the invention.

As shown in the drawings, there may be provided a box housing 10 having rear side 11, front side 12, ends 13, bottom 14 and a demountable top 15. Mounted in a bearing 16 carried by side 11 is an input shaft 17 extending inside and outside of the side 11. The end of the shaft 17 has a sprocket 18 keyed thereto. A source of power, and as shown, an electric motor and in most instances a constant speed motor 19 has its driving

2

shaft 20 coupled to the shaft 18 through a chain drive 21. As the motor drives shaft 20, the chain 21 drives the input shaft 17 through the sprocket 18 to continuously drive input shaft 17. Spaced from shaft 17 and disposed parallel thereto is an input shaft 22 mounted in a bearing 23 carried by side 11. This shaft 22 also extends inside and outside of the side 11 and secured to its outer end is a coupling device 24 which may be operatively connected to mechanism which is to be intermittently driven.

Located in the box 10 and keyed to that end of shaft 17 located therein is an eccentric plate 25 having pivot pin 26 keyed thereto. Also located in box 10 is an intermittent plate disc 27 keyed to that end of shaft 22 located in said box. The diameter of the plate disc 27 is preferably about twice that of the eccentric plate 25. A plurality of and as shown, eight needle roller bearings 31—38 are rotatably mounted on the disc 27. These roller bearings 31—38 are disposed on a common circumferential center line near the outer periphery of said plate 27 and are spaced equidistantly from each other. Located to one side of plate 27 remote from plate 25 and integral with side 11 is a bearing 40 extending into said box. A pivot 41 is mounted in said bearing 40 and has integral therewith a slide box 42 having integral therewith an upwardly extending trunnion lever 43 at the front thereof. The central axes of the pivot 41 and shaft 17 are located on a line which is at right angles to a diameter of shaft 22 and which is located materially below said shaft 22. The upper free end of lever 43 has a slot 44 therein defining a pair of fingers 45. A bearing 46 is mounted on side 11, is integral therewith and extends into box 10. The bearing 46 is located behind the extension 43 and has mounted therein a pivot 47. Integral with the pivot 47 is a trunnion lever 48 whose upper free end has a slot 49 therein defining fingers 50. A roller bearing 51 is disposed in slot 44 and has an annular flange 52 lapping over the fingers 45. Mounted on the side 11 and extending into box 10 is support 55 integral with side 11. Mounted on said support 55 is a slide box 57 having an elongated slot 58 in the rear part of the front plate thereof. Slideably mounted in said slide box 57 is a slide bar 59 having a slot 60 in one end thereof defining fingers 61. Carried by the slide bar 59 and extending through slots 58 and 49 is a roller bearing 62 having a flange 63 integral therewith and lapping over finger 50. Eccentrically and pivotally connected to the shaft 17 is a drive bar 65 having

one end thereof pivotally connected to the pivot 26 and its other end extending through the pivoted slide box 42. The rear face of the slide bar 65 has a pair of spaced recesses 66 accommodating inserts integral with driving blocks 67 secured to operating bar 65. The distance between the blocks is equal to the diameter of each of the needle roller bearings 31—38.

The operation of the mechanism shown in Figs. 1—5 is as follows: The input shaft 17 is continuously driven by the motor 19 and is the main continuous drive shaft whose direction of rotation is shown in Figs. 3—5. With the movable parts disposed in the relationship shown in Fig. 3, the operable drive blocks 67 are in inoperative position and the slide lock bar 59 is in operative position with the roller bearing 34 located in the slot 60 thereof thereby locking and maintaining stationary the output shaft 22. As the eccentric plate 25 is driven by the shaft 17 to move the pin 26 from point A to point B, the slide drive bar 65 is moved in a direction away from slide box 57 and towards shaft 17 and that end of bar 65 swingable about pivot 26 is moved downwardly and then upwardly until it has described a semi-circle. Immediately upon leaving point A, the drive blocks 67 begin to retract and are completely out of engagement with roller bearing 32 and the lock bar 59 is simultaneously moved forward to locking position to locate the fingers 61 into locking engagement with roller bearing 34. Upon continued movement of the pivot 26 through an angle of 90° from point A to the position shown in Fig. 3, the bar 65 continues to retract, its pivoted end swings to its maximum lower position to move the drive blocks 67 to their maximum position away from the roller bearings 31—38 and the slide box 42 and trunnion 43 are swung to a maximum position to actuate the lock bar 59 to its maximum forward locking position. In the course of travel of pivot 26 from its position shown in Fig. 3 to point B, the pivot 26 travels another 90° and the bar 65 continues to retract and reaches its maximum retracted position and also swings upwardly about the fulcrum of slide box 42. This action swings slide box 42 acting through trunnion 43 to retract slide bar 59 and also moves the drive blocks 67 towards the next roller bearing 31. As the pivot 26 reaches the point B, the relationship of parts is shown in Fig. 4 where the slide bar 65 is at dead center, with the lock bar 59 just about to disengage the roller bearing 34 and the drive blocks just about to engage roller bearing 31. Upon continued rotation of shaft 17 to move the pin 26 from the point B to point C, and immediately upon leaving point B, the lock bar 59 is completely disengaged from roller bearing 34 and the drive blocks engage the roller bearing 31. As the pivot 26 moves from point B to the position shown in Fig. 5, the bar 65 moves forwardly and its end pivoted at 26 moves upwardly, whereupon the slide block 42 and its trunnion 43 swing about the slide box fulcrum to a maximum position when pin 26 reaches the position shown in Fig. 5 whereupon the bar 59 is at its maximum retracted position and the plate 27 has been moved through an angle of 22.5°. As the pivot 26 is moved from the position shown in Fig. 5 back to original point B, the bar 65 still moves forwardly and its pivoted end at 26 now moves downwardly further to drive the plate 27 through an additional angle of 22.5° and to swing the block 42 to feed the slide bar 59 towards locking position. When the pivot 26 reaches position B,

the slide block 42 has been rocked to such position as to act through trunnion 43 to actuate slide bar 59 to initial locking position and the blocks 67 are just about to become engaged with the roller bearing 38. The cycle of operation of parts is continued to provide an intermittent movement. In this embodiment, instead of having roller bearings on the intermittent plate 27, and a slot between the blocks 67, the plate 27 may be slotted and the drive blocks 67 may be replaced by a driving pin or roller bearing in the manner shown in Fig. 10. If this is done, the configuration of the periphery of the plate 27 may be also modified so as to be similar to that of the intermittent plate of Fig. 10.

Another embodiment of the invention is shown in Figs. 6 and 7 having three bearings 100, 101 and 102 carried by side 11 of box 10. Mounted in bearings 100 and 101 respectively are input shaft 117 and output shaft 122. The continuous drive shaft 117 has an eccentric plate cam lock 103 keyed thereto. The eccentric 103 is essentially a circular disc having a portion thereof cut away at 104 to provide clearance and a locking portion 105 during rotation of eccentric 103. Keyed to the shaft 122 is an intermittent plate 127 whose diameter may be twice that of the eccentric 103. Eight needle roller bearings 131—138, located equidistantly from each other, are rotatably mounted on plate 127 and are disposed on a common circumferential line near the outer periphery of plate 127. The outer periphery of plate 127 between each pair of roller bearings 131—138 is cut away to provide arcuate cut-outs 106. The radius of each of said cut-outs 106 is the same as the radius of the lock portion 105 of the eccentric.

Mounted in bearing 102 is a pivot 107. One end of a swing lever arm 108 is pivotally mounted on pivot 107 and its other end carries a pivot 109. An operating or drive lever bar 165 has one end thereof pivotally mounted on pivot 109 and its other end pivotally and eccentrically connected to eccentric 103 through a pivot pin 126 carried by eccentric 103. In this embodiment, the parts may be in such relationship as shown in Fig. 6 that a straight line may be drawn transversely through the central longitudinal axes of the pivots 126, 109 and shaft 117 and is at right angles to a diameter of shaft 122. Secured to the drive bar 165 are a pair of drive blocks 167 spaced from each other a distance equal to the diameter of roller bearings 131—138.

The operation of the mechanism shown in Figs. 6 and 7 is as follows:

At that stage of operation when the parts are located in the relative positions shown in Fig. 6, the locking portion 105 of the eccentric cam lock is just about in unlocking position and the slide bar 165 has been moved over to its maximum right hand position whereupon the ends of the drive blocks 167 just about engage the roller bearing 131. Upon 180° rotation of the shaft 117 and plate 103, the lever 108 swings pivot pin 107 to the point A and that end of the bar 165 pivoted to pin 126 moves forwardly and upwardly and then forwardly and downwardly whereby the drive blocks 167 drive the plate 127 through the roller bearing 131 which at the end of the forward movement of bar 165 reaches the position originally occupied by bearing 138. When bearing 131 reaches that position, the leading end of locking portion 105 comes into contact with a cut-out 106 to lock the intermittent plate in position and simultaneously the blocks

167 disengage the roller bearing 131. Upon the next 180° rotation of shaft 117, the bar 165 moves downwardly rearwardly and then downwardly forwardly until the pivot 126 reaches the position shown in Fig. 6. In the course of this particular movement of shaft 117, the portion 105 is continuously in contact with arc 106 to lock the shaft 122 against rotation while the blocks 167 were completely inoperative and the lever 108 is swung to its original position. The 360° cycle is repeated to provide intermittent movement of the shaft 122.

The modification shown in Figs. 8 and 9 is similar to that shown in Figs. 6 and 7 and differs therefrom in that the elements 107, 108 and 109 are eliminated and two simultaneously operating eccentric plate cam locks 103 are employed and the ends of the slide bar 165 are pivotally connected to the pivot pins 126 carried by these eccentrics 103. The shafts 117 are driven by a common main drive 117' through gears 70 keyed to said shafts.

The modification shown in Figs. 10 and 11 is similar to that shown in Figs. 8 and 9 and differs therefrom in the substitution of a drive roller bearing 367 on the drive bar 165 in place of the drive blocks, and the elimination of the roller bearings 131-138 and the substitution of slots 331-338 therefor.

The modification shown in Fig. 12 is the same as that shown in Fig. 6 with the following additions: Another drive shaft 417 is remote from the shaft 117 and is a continuous drive through a chain 470 coupled with sprockets 471 keyed to shafts 117 and 417. Another shaft 422 is remote from shaft 122 and is driven by a chain 473 coupled with sprockets 474 keyed to shafts 422 and 122. The shafts 417 and 422 respectively have keyed thereto intermittent plates 127 and 103. With this embodiment of the invention, the intermittent locked movement may be affected at a plurality of locations of operation.

In all of the embodiments of the invention, the slots in the intermittent plate and the drive roller bearing on the drive bar as shown in Figs. 10 and 11 may be employed in place of the rollers on the intermittent plate and the drive blocks on the drive bar as shown in the other figures.

I claim:

1. Mechanism for converting continuous rotary motion to intermittent motion comprising a rotatable input shaft, a rotatable output shaft, a drive bar, one end of said drive bar being pivotally and eccentrically associated with said input shaft, means for intermittently actuating said output shaft and including said input shaft and said drive bar, means supporting the other end of said drive bar and being independent of said output shaft and means operatively connected to said input shaft for intermittently locking said output shaft and including a member secured to said output shaft and a member secured to said input shaft, the periphery of a portion of each of said members being an arc of a circle, the radii of said arcs being substantially the same.

2. Mechanism for converting continuous rotary motion to intermittent motion comprising a rotatable input shaft, a rotatable output shaft, a drive bar, one end of said drive bar being pivotally and eccentrically associated with said input shaft, means for intermittently actuating said output shaft and including said input shaft and said drive bar, means supporting the other end of said drive bar and being independent of said output shaft and means operatively connected

to said input shaft for intermittently locking said output shaft and including a member secured to said output shaft and a member secured to said input shaft, the periphery of a portion of each of said members being an arc of a circle, the radii of said arcs of both of said members being substantially the same.

3. Mechanism for converting continuous rotary motion to intermittent motion comprising a rotatable input shaft, a rotatable output shaft, a drive bar, one end of said drive bar being pivotally and eccentrically associated with said input shaft, means for intermittently actuating said output shaft and including said input shaft and said drive bar, a pivot disposed at a substantially fixed location, a link having one end thereof connected to said pivot, the other end of said drive bar being pivotally connected to the other end of said link and means operatively connected to said input shaft for intermittently locking said output shaft and including a member secured to said output shaft and a member secured to said input shaft, the periphery of a portion of each of said members being an arc of a circle, the radii of said arcs being substantially the same.

4. Mechanism for converting continuous rotary motion to intermittent motion comprising a rotatable input shaft, a rotatable output shaft, a drive bar, one end of said drive bar being pivotally and eccentrically associated with said input shaft, means for intermittently actuating said output shaft and including said input shaft and said drive bar, a pivot disposed at a substantially fixed location, a link having one end thereof connected to said pivot, the other end of said drive bar being pivotally connected to the other end of said link and means operatively connected to said input shaft for intermittently locking said output shaft and including a member secured to said output shaft and a member secured to said input shaft, the periphery of said first mentioned member including a plurality of individual arcs of a circle, the periphery of a portion of said second mentioned member being an arc of a circle, the radii of said arcs of both of said members being substantially the same.

5. Mechanism for converting continuous rotary motion to intermittent motion comprising a rotatable output shaft, a rotatable input shaft, a drive bar, one end of said drive bar being pivotally and eccentrically associated with said input shaft, means for intermittently actuating said output shaft and including said input shaft and said drive bar, a pivoted slide box, the other end of said drive bar slideably mounted in said box and means operatively connected to said slide box for intermittently locking said output shaft.

6. Mechanism for converting continuous rotary motion to intermittent motion comprising a plurality of rotatable input shafts, a rotatable output shaft, a drive bar, one end of said drive bar being pivotally and eccentrically associated with one of said input shafts, the other end of said drive bar being pivotally and eccentrically associated with another of said input shafts, means for intermittently actuating said output shaft and including said input shafts and said drive bar and means operatively connected to each of said input shafts for intermittently locking said output shaft.

7. Mechanism for converting continuous rotary motion to intermittent motion comprising a plurality of rotatable input shafts, a rotatable out-

put shaft, a drive bar, one end of said drive bar being pivotally and eccentrically associated with one of said input shafts, the other end of said drive bar being pivotally and eccentrically associated with another of said input shafts, means for intermittently actuating said output shaft and including said input shafts and said drive bar and means operatively connected to each of said input shafts for intermittently locking said output shaft and including a member secured to 10 said output shaft and a member secured to each of said input shafts, the periphery of said first mentioned member including a plurality of individual arcs of a circle, the periphery of a portion of each of said members secured to said input shafts being an arc of a circle, the radii of said arcs of said three members being substantially the same.

8. Mechanism for converting continuous rotary motion to intermittent motion comprising a rotatable input shaft, a rotatable output shaft, a reciprocable drive bar, a pair of drive blocks secured to said drive bar intermediate the ends of said drive bar, one end of said drive bar being pivotally and eccentrically associated with said input shaft and being reciprocable thereby, means supporting the other end of said drive bar and being independent of said output shaft, means secured to said output shaft and intermittently engageable by said drive blocks upon reciprocation of said drive bar to intermittently drive said output shaft, and means operatively connected to said input shaft for intermittently locking said output shaft and including a member secured to said output shaft and a member secured to said input shaft, the periphery of a portion of each of said members being an arc of a circle, the radii of said arcs being substantially the same.

9. Mechanism for converting continuous rotary motion to intermittent motion comprising a rotatable input shaft, a rotatable output shaft, a reciprocable drive bar, a pair of drive blocks intermediate the ends of said drive bar, one end of said drive bar being pivotally and eccentrically associated with said input shaft and being reciprocable thereby, means supporting the other end of said drive bar and being independent of said output shaft, a plate secured to said output shaft, a plurality of rollers carried by said plate, spaced equidistantly from each other, disposed on the circumference of a circle and being individually and intermittently engageable by said drive blocks upon reciprocation of said drive bar to intermittently drive said output shaft, and means operatively connected to said input shaft for intermittently locking said output shaft and including a member secured to said output shaft and a member secured to said input shaft, the periphery of a portion of each of said members being an arc of a circle, the radii of said arcs being substantially the same.

10. Mechanism for converting continuous rotary motion to intermittent motion comprising a rotatable input shaft, a rotatable output shaft, a reciprocable drive member, one end of said drive member being pivotally and eccentrically associated with said input shaft and being continuously reciprocable thereby, a member secured to said output shaft, one of said members having a slot therein, a roller carried by the other of said members and being intermittently engageable in said slot upon reciprocation of said drive member to intermittently drive said output shaft, a pivot disposed at a substantially fixed location,

5 a link having one end thereof connected to said pivot, the other end of said drive member being pivotally connected to the other end of said link and means operatively connected to said input shaft for intermittently locking said output shaft and including an element secured to said output shaft and an element secured to said input shaft, the periphery of a portion of each of said elements being an arc of a circle, the radii of said arcs being substantially the same.

11. Mechanism for converting continuous rotary motion to intermittent motion comprising a rotatable input shaft, a rotatable output shaft, a reciprocable drive bar, a pair of drive blocks secured to said drive bar intermediate the ends of said drive bar, one end of said drive bar being pivotally and eccentrically associated with said input shaft and being continuously reciprocable thereby, a pivot disposed at a substantially fixed location, a link having one end thereof connected to said pivot, the other end of said drive bar being pivotally connected to the other end of said link, means secured to said output shaft and intermittently engageable by said drive blocks upon reciprocation of said drive bar to intermittently drive said output shaft, and means operatively connected to said input shaft for intermittently locking said output shaft and including a member secured to said output shaft and a member secured to said input shaft, the periphery of a portion of each of said members being an arc of a circle, the radii of said arcs being substantially the same.

12. Mechanism for converting continuous rotary motion to intermittent motion comprising a rotatable input shaft, a rotatable output shaft, a reciprocable drive bar, a pair of drive blocks secured to said drive bar intermediate the ends of said drive bar, one end of said drive bar being pivotally and eccentrically associated with said input shaft and being continuously reciprocable thereby, a pivot disposed at a substantially fixed location, a link having one end thereof connected to said pivot, the other end of said drive bar being pivotally connected to the other end of said link, a plate secured to said output shaft, a plurality of rollers carried by said plate, spaced equidistantly from each other, disposed on the circumference of a circle and being individually and intermittently engageable by said drive blocks upon reciprocation of said drive bar to intermittently drive said output shaft, and means operatively connected to said input shaft for intermittently locking said output shaft and including a member secured to said output shaft and a member secured to said input shaft, the periphery of a portion of each of said members being an arc of a circle, the radii of said arcs being substantially the same.

13. Mechanism for converting continuous rotary motion to intermittent motion comprising a rotatable output shaft, a rotatable input shaft, a reciprocable drive bar, a pair of drive blocks secured to said drive bar intermediate the ends of said drive bar, one end of said drive bar being pivotally and eccentrically associated with said input shaft and being continuously reciprocable thereby, means secured to said output shaft and intermittently engageable by said drive blocks upon reciprocation of said drive bar to intermittently drive said output shaft, a pivoted slide box, the other end of said drive bar slideably mounted in said box and means operatively connected to said slide box for intermittently locking said output shaft.

14. Mechanism for converting continuous rotary motion to intermittent motion comprising a rotatable output shaft, a rotatable input shaft, a reciprocable drive bar, a pair of drive blocks secured to said drive bar intermediate the ends of said drive bar, one end of said drive bar being pivotally and eccentrically associated with said input shaft and being continuously reciprocable thereby, a plate secured to said output shaft, a plurality of rollers carried by said plate, spaced equidistantly from each other, disposed on the circumference of a circle and being individually and intermittently engageable by said drive blocks upon reciprocation of said drive bar to intermittently drive said output shaft, a pivoted slide box, the other end of said drive bar slideably mounted in said box and means operatively connected to said slide box for intermittently locking said output shaft.

15. Mechanism for converting continuous rotary motion to intermittent motion comprising a plurality of rotatable input shafts, a rotatable output shaft, a reciprocable drive bar, a pair of drive blocks secured to said drive bar intermediate the ends of said drive bar, one end of said drive bar being pivotally and eccentrically associated with one of said input shafts, the other end of said drive bar being pivotally and eccentrically associated with another of said input shafts, means secured to said output shaft and intermittently engageable by said drive blocks upon reciprocation of said drive bar to intermittently drive said output shaft, and means operatively connected to each of said input shafts for intermittently locking said output shaft.

16. Mechanism for converting continuous rotary motion to intermittent motion comprising a plurality of rotatable input shafts, a rotatable output shaft, a reciprocable drive bar, a pair of drive blocks secured to said drive bar intermediate the ends of said drive bar, one end of said drive bar being pivotally and eccentrically associated with one of said input shafts, the other end of said drive bar being pivotally and eccentrically associated with another of said input shafts, a plate secured to said output shaft, a plurality of rollers carried by said plate, spaced equidistantly from each other, disposed on the circumference of a circle and being individually and intermittently engageable by said drive blocks upon reciprocation of said drive bar to intermittently drive said output shaft, and means operatively connected to each of said input shafts for intermittently locking said output shaft.

17. Mechanism for converting continuous rotary motion to intermittent motion comprising a rotatable input shaft, a rotatable output shaft, a reciprocable drive member, one end of said drive

member being pivotally and eccentrically associated with said input shaft and being continuously reciprocable thereby, means supporting the other end of said drive member and being independent of said output shaft, a member secured to said output shaft and having a plurality of radial slots therein spaced equidistantly from each other, means carried by said drive member and being intermittently engageable in said slots upon reciprocation of said drive member to intermittently drive said output shaft, and means operatively connected to said input shaft for intermittently locking said output shaft and including a member secured to said output shaft and a member secured to said input shaft, a portion of the periphery of each of said last two mentioned members being an arc of a circle, the radii of said arcs being substantially the same.

18. Mechanism for converting rotary motion to intermittent motion comprising a pair of rotatable input shafts, a rotatable output shaft, a reciprocable drive member, one end of said drive member being pivotally and eccentrically associated with one of said input shafts, the other end of said drive member being pivotally and eccentrically associated with the other of said input shafts, a plate secured to said output shaft, said plate having a plurality of radial slots therein spaced equidistantly from each other, means carried by said drive member and being intermittently engageable in said slots upon reciprocation of said drive member to intermittently drive said output shaft, means operatively connected to said input shafts for intermittently locking said output shaft and including a member secured to each input shaft, and said member secured to said output shaft, a portion of the periphery of each of said members secured to said input shafts being an arc of a circle, a portion of the periphery between two successive slots of said plate being an arc of a circle, the radii of all of said arcs being substantially the same.
